UNITED STATES PATENT OFFICE.

EDWARD B. HESS, OF NEW YORK, N. Y., ASSIGNOR, BY MESNE ASSIGNMENTS, TO
ROYAL TYPEWRITER COMPANY, INC., OF NEW YORK, N. Y., A CORPORATION OF
NEW YORK.

WRITING-MACHINE.

1,094,146.

Specification of Letters Patent. Patented Apr. 21, 1914.

Original application filed May 15, 1907, Serial No. 373,849. Divided and this application filed July 10, 1911. Serial No. 637,760.

To all whom it may concern:

Be it known that I, EDWARD B. HESS, a citizen of the United States of America, residing in the borough of Manhattan, city, county, and State of New York, have invented a certain new and useful Improvement in Writing-Machines, of which the following is a specification.

This invention comprises a new organization wherein margin paper-holding or clamping devices are adjustable simultaneously with margin stop devices and in the organization shown the margin paper-holding or clamping devices are mounted upon and movable with the margin stop devices.

In the accompanying drawing: Figure 1 is a vertical longitudinal section of so much of a front strike typewriting machine as is deemed desirable to illustrate the invention: Fig. 2, a rear elevation: Fig. 3, a detail plan view of combined margin stop and margin paper-clamping devices: and Fig. 4, a rear elevation of a margin stop device, the margin paper-holding devices not being shown in this view.

X and Y indicate the side or end plates of a carriage of which S is the rack bar and S¹ the ordinary cylindrical platen mounted to turn in the end plates. In rear of the platen, there is mounted in the end plates a transversely disposed rack bar N having coincident and equally spaced teeth on its upper and rear surface. On this bar are adjustably mounted right and left hand margin stops K and intermediate stops M that may be used for tabulation purposes.

J is the center or frame stop pivoted upon the frame at j and adapted to be moved transversely of the rack bar N. In the particular construction illustrated, the center stop J is so arranged as to be out of the path of the adjustable stops M but in the path of the margin stops K. The intermediate or tabular stops M are bifurcated so as to embrace and closely fit in the spaces between the upper and side teeth of the rack bar. The margin stops may each be constructed as follows: Each has a pivoted spring latch

K² adapted to engage the spaces between the teeth on the upper surface of the bar N and is pivoted on a stop frame K³ that straddles the rack bar and is held in position thereon by cross pins k extending beneath the bar between lugs on opposite sides of the frame. The part of the stop against which abuts the frame stop lever J is the head k¹ of an adjustable screw turning in a threaded opening in a lateral projection or block on one of the sides of the frame K³ and having applied to its threaded end a lock nut k². A beveled plate k³ carried on the upper surface of the projection in which the screw is mounted serves to snub the stop lever out of the way when the carriage is moved in one direction whereas the stop lever J is engaged by the head k¹ when the carriage moves in the other direction. The stop lever J is shown as a straight lever and below its pivot it fits between the arms of a rocking bifurcated arm O fast on a rock shaft O¹ pivoted in the frame of the machine and having at its right hand end an upright projection O² attached by a link O³ to a vertically disposed lever arm O⁴ located at the right hand side of the key board of the machine. Springs o, o, bearing respectively upon opposite sides of the vertically disposed bifurcated part O tend to maintain it in central or vertical position. Above the pivot j of stop lever J, the latter has an adjustable screw o¹ that engages the lower end of a rack releasing lever I, whose upper end lies under a horizontal flange of the escapement or feed rack S of the machine. This rack is carried in the ends of levers s s pivoted at s¹ on the side plates of the carriage and having applied to their ends springs s² the reaction of which tends to hold the rack in engagement with the pinion S² of the escapement devices. When lever arm O⁴ is drawn to the front, the upper end of stop lever J is rocked away from the stop bar N. This movement is of such extent as to disengage the lever J from the part k¹ of the margin stop to thereby permit of the writing of one or more let-

ters at the end of a line. When lever arm 65 O⁴ is pressed rearwardly, the upper end of lever J will be swung toward the intermediate or tabular stops and this occurs to 5 such extent as to cause such lever to engage a stop M on the stop bar. In tabulating work this movement causes lever I to 10 disengage rack S from the escapement pinion S² so that the carriage will run free until a tabular stop M engages the frame stop P.

Pivoted at p on the right hand side of stop lever J at a suitable point above the pivot j of the latter is a plate P whose axis p is at 15 right angles to axis j. This plate extends upwardly substantially as far as the stop lever J and is normally held away from the latter by re-action spring p¹. An extension P¹ from plate P extends a suitable distance 20 below its pivot and is connected by link P² with a radial arm Q on the upper end of a vertical rock shaft Q¹ having near its lower end a radial arm Q² from which extends forward a link Q³ connected at its front end 25 with a radial arm q¹ on a transverse rock shaft q. This rock shaft q has extending upward from it a key lever locking plate q² which normally is inclined slightly forward from a vertical line.

30 R indicates a character key lever of which there will be the usual number. Near the front end of each key lever is a downward projection r the front edge or corner of which is closely adjacent the locking plate q². When the stop J P is engaged by either 35 a margin stop or a tabular stop when the carriage is moving during the progress of the printing operation, plate P will be carried against the side of stop J and in its 40 movement will effect a movement of rock shaft q that will carry the locking plate q² under the projections r on the key levers and lock them against operation.

The paper table in the special construction 45 illustrated is divided into two parts a hinged upper part U and a fixed lower part U². Between the two parts of the table there is an opening u which is opposite or horizontally in line with the front side or 50 face of the frames of the right and left hand margin stops. Secured to and projecting from each margin stop frame is a plate or arm V that extends through the transverse opening u. Hinged to this arm at v is a 55 margin paper clamp consisting of an arm W extending forward over and around the surface of the platen. In this arm is preferably placed a pressure or margin paper clamp roll W¹ bearing upon the platen and in rear 60 of which is a recess W² in which the edge of the paper that is being printed upon traverses. In rear of the hinge b there is fastened to the upper surface of the arm V

a leaf spring v¹ that extends over the hinge and bears upon the plate W and by its re-action serves to press the paper clamp or pressure roller W¹ against the surface of the platen. When, however, the paper clamp is swung upwardly upon its hinge out of the way, or into inoperative position, the end of 70 the spring v¹ passes into an aperture v² in the plate or arm W and when the arm is swung sufficiently far back, the reaction of the spring tends to hold the paper clamp in elevated position. In order that the operator 75 may adjust the margin stop and with it the margin paper-clamp without reaching back to the body of the stop and without disturbing the hinged portion U of the paper table, there is provided a lever Z pivoted 80 upon the outer side of the arm or plate V and projecting rearwardly through the transverse opening U in the paper table. On the ends of spring latch K² of the margin stop, there is a projecting pin z that 85 overlies lever Z. By depression, therefore, of the lever, the latch may be disengaged from the toothed stop bar and the margin stop and with it the paper-clamp be adjusted longitudinally of the stop bar and 90 platen. This arrangement by which the margin paper clamp and the margin stop may be simultaneously adjusted is believed 95 to be a novel feature in writing machines and has manifest advantages. The construction illustrated moreover possesses the further advantage that a single transverse stop bar is made to serve both as a support for the margin stop and for intermediate or tabular stops as well as for paper margin 100 clamps.

The invention is shown applied to a front strike machine. It is, however, not restricted to machines of that type.

This application is a division of my application filed May 15, 1907 Serial Number 873,849.

No claim is made herein to the special line lock devices which form the subject-matter of another application.

I claim:

1. The combination of a typewriter carriage, a platen mounted therein, a paper table divided longitudinally of the platen with a space between its adjacent edges, an 115 adjustable margin stop located behind the paper table, and a margin clamp device mounted on the margin stop and extending through the opening in the paper table into operative relation to the platen.

2. The combination of a typewriter carriage, a platen mounted therein, a paper table divided longitudinally of the platen with a space between its adjacent edges, an adjustable margin stop located behind the 125 paper table, an arm attached to the margin

stop and extending through the opening in the paper table and a margin clamping member hinged in the end of said arm.

3. The combination of a typewriter carriage, a platen mounted therein, a paper table, an adjustable paper clamp, means at the rear of said paper table for supporting said clamp, locking means for securing said clamp in an adjusted position on said sup-

porting means, and releasing devices for 10 said locking means, said releasing devices extending in front of said paper table.

In testimony whereof, I have hereunto subscribed my name.

EDWARD B. HESS.
